UNITED STATES PATENT OFFICE.

WILLIAM H. PAGE, OF NORWICH, CONNECTICUT.

STEAM AND HOT-WATER HEATER.

SPECIFICATION forming part of Letters Patent No. 668,841, dated February 26, 1901.

Application filed June 7, 1900. Serial No. 19,482. (No model.)

To all whom it may concern:

Be it known that I, WILLIAM H. PAGE, a citizen of the United States, residing at Norwich, in the county of New London and State 5 of Connecticut, have invented certain new and useful Improvements in Steam and Hot-Water Heaters, of which the following is a full, clear, and exact description.

This invention is in the boilers of steam-10 generators and hot-water heaters of the class used commonly in house-heating, and my immediate purpose is to provide a boiler-section in which the water shall be so presented to the furnace-fire as to receive the greatest benefit and influence from the caloric products 15 of said fire and in which the heated water may have unobstructed circulation. Incidentally I have improved other features of such heaters, all being clearly described and explained 20 hereinafter.

My newly-invented heater is of the vertical sectional type; and it consists, mainly, of a number of superimposed sections—viz., the base or ash-pit section having mounted thereon 25 the boiler-section and the latter in turn supporting the dome-section, the said sections each being adapted to be cast as a single structure. The said boiler-section and the lower portion of the dome-section are inclosed with- 30 in and by a cylindrical shell concentric with the vertical central line of the heater and serving to provide a circular air-space around the boiler-section and the said lower portion of the dome-section, through which air-space 35 the products of combustion are adapted to circulate and from which said products pass into a smoke-chamber secured to the outer face of the said cylindrical shell. From the smoke-chamber just mentioned said products 40 finally pass off through a smoke-pipe.

To assist in the explanation of my invention, I have provided the accompanying three sheets of drawings, illustrating the same, as follows:

45 Figure 1 illustrates a heater embodying my improvements and shows said heater partly in front elevation and partly in central vertical section in order that the interior construction thereof may be exposed to view. 50 Fig. 2 is a central vertical sectional view of my newly-invented heater, said section being

taken in a vertical plane at right angles to the plane of the sectioned portion of Fig. 1. Figs. 3 and 4 are cross-sectional views of my heater, the same being taken, respectively, on the 55 lines 3 3 and 4 4 of Fig. 2. Fig. 5 shows in cross-section a certain element of my heater pertaining to the grate. Fig. 6 illustrates in central vertical section the dome portion of my heater specially fitted up for hot-water 60 heating.

Referring to the drawings, the letter *a* denotes as a whole the ash-pit section, *b* the boiler-section, and *c* the dome-section, of my 65 heater.

The ash-pit section *a* consists of a circular shell 10, preferably slightly tapering, as shown, and having formed upon its upper edge a circular plate 10^a to receive the boiler-section *b* and the above-mentioned cylindrical shell, which incloses the said boiler-section. 70

The boiler-section *b* consists of a hollow circular side wall 11 of slightly-diminishing diameter from its lower to its upper end and 75 the said upper (smaller) end of the boiler-section is almost entirely closed over by a crown-sheet 11^a, which latter also consists of a hollow wall, thereby providing a chamber connecting with that of the hollow circular 80 inclosing wall 11 of the boiler-section.

The space inclosed by the circular hollow wall 11 of the boiler-section *b* is utilized as the fire-pot of the heater, and in order to permit of access thereto and to provide an exit 85 for the products of combustion generated therein the crown-sheet 11^a and the circular side wall 11 of the boiler-section have an opening 11^b extending therethrough, which latter registers with the feed-door of the 90 heater, as hereinafter explained.

The just-mentioned circular space inclosed by the hollow circular wall 11 of the boiler-section (which space is utilized as the fire-pot of the heater) is divided diametrically by a 95 hollow wall 11^c, located in a vertical plane dividing centrally the opening 11^b, and adjacent said opening the wall 11^c is cut back, as best shown in Figs. 2 and 3, to provide a considerable clear space in the rear of the 100 feed-door, hereinafter described. The wall 11^c is approximately of the same thickness as

the circular wall 11 and extends from the plane of the lower end of the boiler-section to the crown-sheet 11^a. The wall 11^c, as before mentioned, is hollow, and at its upper 5 end the chamber therein opens into the chamber in the crown-sheet, and at the points of junction of the wall 11^c with the circular side wall 11 the said chamber within the wall 11^c opens into that of the circular 10 side wall 11 from the lower end of said chamber to a point substantially midway its height, as is best seen in Fig. 2.

As already mentioned, the dome-section C is mounted upon the boiler-section b, and the 15 lower wall 12 thereof, adjacent the crown-sheet of the boiler-section, is concave to provide an open space 13 between the said boiler and dome, and the upper wall 12^b of the dome c is preferably convex, as shown, and has an 20 outlet-pipe 14 leading from its highest point. The chamber within the dome-section c and that within the upper portion 11^a of the boiler-section b are connected by a number of short 25 pipes or nipples 15, which cross the open space 13 between the said boiler and dome sections. Two of the said nipples are located immediately over the water-chamber provided by and between the walls 11^c to provide a direct 30 upward discharge from said water-chamber into the boiler-section, while the other nipples are offset from the said water-chamber, as best seen in Fig. 3, to provide passages for the downward or return flow of water.

I have already referred to the cylindrical 35 shell d, which serves to inclose the boiler-section and the lower portion of the dome-section of the heater. The said shell at its lower end rests upon and is secured to the circular plate 10^a of the ash-pit, and at its upper end 40 the said shell engages and is secured to an overhanging circular ledge 12^c of the dome-section c. The cylindrical shell d when in position provides clear space in the form of a circular chamber 16, which incloses the 45 boiler-section b and the lower portion of the dome-section c, as first above described, the upper and lower ends of said chamber being respectively closed by the ledge portion 12^c of the dome-section and the circular plate 10^a of 50 the ash-pit section.

Referring again to the opening 11^b, extending through the crown-sheet 11^a and the circular wall 11 of the boiler-section, it will be seen that by reason of such opening communication is established between the fire-pot and the clear space in the rear of the feed-door and also that the said opening 11^b connects with the chamber 13 (between the boiler and dome sections) at the point in said chamber 13 approximately diametrically opposed to the opening 11^b, or, in other words, at the rear side of said chamber a passage-way 13^a is provided leading through the concave wall 12 of the dome-section and serving to connect 65 the said chamber 13 with the circular chamber 16, already described.

The reference-number 17 denotes a smoke-box which is secured to the cylindrical shell d at the rear side of the heater, and the reference-numbers 17^a 17^b denote openings provided in the cylindrical shell d, through which communication may be established between the chamber 16 and the said smoke-box, which latter also has leading therefrom the smoke-pipe 17^c.

It will now be seen that through the opening 11^b, the passage 13^a, and the openings 17^a 17^b a draft-passage is established between the fire-pot and the chamber 13, thence from the latter to the chamber 16, and finally from 80 said chamber 16 to the smoke-box 17 and smoke-pipe 17^c.

The products of combustion pass from the fire through the above-prescribed course; but in order to provide both a direct and indirect 85 draft, which latter has for its object to utilize to the fullest possible extent the caloric properties of the said products, the circular chamber 16 is divided at a point somewhat below the opening 17^a by a circular plate 16^a, 90 which separates the chamber 16 into upper and lower portions between which communication is established at the front side of the heater by stopping off the plate 16^a for some little distance, as best shown in Fig. 3. 95

The reference-number 18 denotes a damper located in the smoke-box and adapted to close the opening 17^a in the cylindrical wall 16. When the damper 18 is open and dropped to the position shown in dotted lines in the drawings, the products of combustion, naturally seeking the first and most direct outlet from the chamber 16, will pass therefrom through the opening 17^a into the smoke-box 17 and out through the smoke-pipe 17^c. Should the 100 damper 18 be closed, however, as shown in the drawings, the said products of combustion are forced to pass to the front side of the heater, and thence downward into the lower portion of the chamber 16—i. e., the portion 105 beneath the plate 16^a—from which the smoke-box is reached through the opening 17^b. To insure against a continued whirling of the draft in the circular chamber 16, I preferably divide the portion of the chamber above the 110 plate 16^a (at the rear of the heater) by a plate 16^b, which also divides centrally said passage 13^a, and at the front side of the heater the chamber 16 is divided beneath the fire-door by a similar plate 16^c, which also divides 115 centrally the opening leading from the upper to the lower portions of the chamber 16.

The feed-door, already referred to, is denoted by the number 19 and is hinged upon a plate 19^a, secured to the outer face of the 125 cylindrical shell d. An open space 19^b leads from the rear of the said plate 19^a into the opening 11^b, through which latter access is had to the fire-pot, and said open space also provides an exit from the fire-pot for the products of combustion, as already fully explained. The open passage 19^b crosses the chamber 16

and at such point of crossing is inclosed by the frame 16^a, which bridges the said chamber. The feed-door 19 is located, as is usual in this class of heaters, over the ash-pit door 20, which latter is hinged to a plate 10^b, secured to the front side of the ash-pit *a*.

Describing the ash-pit *a* more fully, the upper end thereof is crossed diametrically by a bar 21, which receives on its upper face the bottom face of the division-wall 11^c of the boiler-section *b*.

The reference-number 22 denotes the grate-bars of the heater, which bars are located in the ash-pit and extend parallel with the bar 21. The said grate-bars 22 are here shown as of the well-known class whose teeth are of triangular shape, as best seen in Fig. 1, and at the back side of the ash-pit the said bars are received by and supported on suitable bearings 10^c, formed on the inner face of the ash-pit wall 10. At the front side of the heater the said grate-bars are journaled in the plate 10^b.

On the inner edge of the circular plate 10^a 25 projections and teeth 10^d are formed to fill up any area at the upper end of the ash-pit not sufficiently covered by the grate-bars to prevent the dropping of coal from the said fire-pot. (See Fig. 4.) The said projections and 30 teeth so far as possible register with the teeth of the grate-bars and incline slightly downward to guide the coal onto the said bars, and in addition to the teeth and projections 10^d ribs 21^a are also provided on the opposite sides 35 of the bar 21, which ribs register with the teeth of the confronting grate-bars, as best shown in Figs. 4 and 5, the said ribs 21^a, like the projections and teeth 10^d, serving, with the grate-bars 22, to form the complete grate. 40 From the description already given it will be understood that the fire-pot is divided centrally by the wall 11^c, and it will also be understood that the bar 21, extending across the ash-pit, correspondingly divides the grate, 45 thus providing a grate for both divisions of the fire-pot, each of said grates being independent of the other.

Each grate-bar 22 bears thereon a gear-wheel 22^a in the rear of the plate 10^b, and the 50 gears of the bars of each division of the grate are in meshing contact. One of the grate-bars of each of said divisions is provided with the usual triangular extension 22^b for the reception of an operating handle or wrench, by 55 means of which the grate-bars may be rocked or turned over.

The reference-number 23 denotes an inlet-pipe leading into the boiler, at the lower end thereof, one or more of which are provided 60 to introduce a supply of water to the boiler as the same may be needed and to provide a return for condensation.

Describing now the action of my heater, assuming the boiler-section to have been supplied with water, filling the circular wall 11, the crown-sheet 11^a, and the cross-wall 11^c,

also the nipples 15 and the lower portion of the dome, and that a sufficient fire is present in the fire-pot, the said fire and the caloric products arising therefrom serve to heat the 70 said water by engagement with the inner face of the circular wall 11, the under face of the crown-sheet 11^a, and the opposite sides of the cross-wall 11^c, and after passing into the chamber 13 the said caloric products engage 75 the upper face of the crown-sheet, the nipples 15, and the lower face of the convex wall 12 of the dome, and, finally, passing into the chamber 16, the said caloric products engage 80 the outer face of the circular wall 11 of the 80 boiler-section. The wall 11^c, extending directly through the fire, is subjected to very great heat, and the water therein becomes heated much more quickly than that in other portions of the heater, and as said water becomes heated it at once commences to rise in the wall 11^c and is displaced by that which is cooler, the latter entering the wall 11^c at its opposite ends from the circular wall 11. The 85 heated water from the wall 11^c, together with 90 that in the crown-sheet 11^a or in the circular wall 11, which is sufficiently heated so to do, passes upward through the nipples 15 into the dome 12, (see arrows, Fig. 1,) when the steam arising therefrom fills the dome and 95 passes off through the pipe 14. The water in the cross-wall 11^c of the boiler-section *b* heats very rapidly, and to prevent its leaving the upper end of the latter faster than its place can be taken by the inflowing cooler water 100 the outlet from said wall into the crown-sheet is considerably less than the combined inlets to said wall, at the opposite ends of the lower portion thereof, said inlets to and outlets from the wall 11^c being denoted, respectively, by 105 the numbers 11^e 11^f in Fig. 2.

As just stated, the heated water from the boiler-section *b* passes upward through the nipples 15 into the dome *c*, and in order to prevent the said heated water from rising in 110 the dome with such force as to shoot through the dome and into the pipe 14 a deflector-plate 24 is located in the said dome over the nipples 15, which plate serves to check the upward force of the heated water and causes 115 it to spread out in the dome, as shown in the drawings.

To prevent the grate-bars 22 from becoming warped when overheated, I provide a central support for the same, which consists of 120 a bar or plate 25, which midway its length receives a bolt 25^a, that extends upward through the cross-bar 21 of the ash-pit, the upper end of said bolt being screwed into the lower edge of the cross-wall 11^c of the boiler-section *b*, as shown in the drawings. The 125 grate-supporting plate 25 when in position extends in a direction at right angles to the grate-bars 22, and midway the length of said bars 22 the said grate-supporting plate enters 130 between the teeth of the said bars, the latter being received in notches 25^b of the said plate,

as is best shown in Figs. 1 and 4, from which it will be seen that the said plate while serving to support the grate-bars interferes in no way with the rotation of the latter.

- 5 The feed-door 19 of my heater is provided on its inner side with a box 19^b, having a number of holes 19^c extending through the inner wall thereof, and openings 19^d into the said box are also provided in the door 19.
 10 The openings 19^d admit air into the box 19^b, which air becomes highly heated in the said box previous to its being drawn therefrom through the holes 19^c into the draft-passage connecting the fire-pot and the chamber 13.
 15 Should there be any gas arising from the fire, said gas when passing the holes 19^c mingles with the heated air and renders the said gas inflammable, thereby gaining additional heat and utilizing the said gas.
 20 The heater is fitted up with the usual appliances whereby it is automatically regulated, also with a water-glass, safety-valve, &c.; but as such features form no part of this present invention it is not considered essential that they be shown or described in detail.
 25 The usual cold-air door 26 is provided in the smoke-box, as shown in Fig. 2.

While I have shown and described my heater as having a fire each side of the cross-wall 11^b of the boiler-section, it will be obvious that a fire could be maintained on one side only of said wall should it be desired to operate the heater under only a partial capacity and in moderate weather. The cross-wall 11^c, dividing the fire-pot centrally, as it does, enables the coal to be readily introduced either at both sides thereof or at one side only, as may be desired, the fire upon one side of the said cross-wall being practically independent of that on the other side.

In Fig. 6 I have shown my heater fitted up for hot-water heating, and when it is desired to thus utilize the same the steam-space within the dome is largely decreased by the introduction of a shell 12^d, which, with the concave wall 12^b of the dome, incloses a chamber 27. It should be understood that the shell 12^d is cast integral with the dome-section *c*, this being readily accomplished by slightly changing the dome-pattern and by coring for the chamber 27. The chamber 27 thus provided may be utilized to receive an isolated supply of water, which when heated to a given point by the circulating water within the dome will 55 by expansion act upon a suitable safety-valve or automatic draft-regulator.

Having thus described my invention, I claim—

1. A boiler-section for heaters of the class referred to, consisting of a fire-pot combined with a water-chamber extending from the grate to the crown-sheet of said boiler, said water-chamber dividing the fire-pot into two independent compartments substantially as 65 specified.

2. A fire-pot section formed with surround-

ing and overhead water-jackets, a water-chamber extending transversely through the said fire-pot, from grate to crown-sheet dividing the fire-pot into two independent compartments, as set forth; said water-chamber being connected with the said surrounding and overhead water-jackets, substantially as 70 specified.

3. A boiler-section consisting in combination of a fire-pot, a water-chamber extending centrally through said fire-pot from grate to crown-sheet dividing the fire-pot into two independent compartments, a water-jacket surrounding and extending over said fire-pot, 75 passages between the opposite edges of the lower portion of the central water-chamber and the surrounding water-jacket, and also between the upper edge of said water-chamber and said overhead water-jacket, all substantially as specified.

4. In combination, a fire-pot section, a water-chamber extending from the grate to the crown-sheet in said fire-pot dividing the said fire-pot into two independent compartments, 80 as set forth, an ash-pit section, grate-bars journaled in said ash-pit section, a central supporting-plate for the said grate-bars, and means for securing said plate to the lower portion of the said water-chamber. 85

5. In combination, a fire-pot section, a superimposed boiler-section, vertical waterways connecting the said fire-pot and boiler sections, a vertical water-chamber located centrally in the fire-pot and extending from 90 grate to crown-sheet, and a deflector-plate located in the boiler-section immediately over the said waterways. 95

6. In combination, a fire-pot section, a superimposed boiler-section, a vertical water-chamber located centrally in the fire-pot and extending from the grate to the crown-sheet, and waterways connecting the fire-pot section and boiler-section; two of said waterways being located immediately over the said 100 water-chamber to provide a direct upward discharge from the water-chamber into the boiler and other of said waterways being offset from said central water-chamber to provide passages for the downward flow of water, all substantially as described. 105

7. In combination, an ash-pit section formed with a central transverse rib 21, a fire-pot section mounted upon the said ash-pit section and formed with a central water-chamber that rests upon the said rib 21 and extends from the said rib to the fire-pot crown-sheet, and grate-bars journaled in the said ash-pit section; the said rib being formed with teeth that register with the teeth of the 110 said grate-bars. 115

8. In combination, in a fire-pot section, a water-chamber centrally located in said fire-pot and extending from the grate to the crown-sheet, and a single feed-door located in the 120 fire-pot wall opposite the edge of the said water-chamber, whereby feed-openings are 125

provided leading into the two half parts of
said fire-pot.

9. In combination, in a boiler, a dome having
a central water-chamber and outlet-pipe
5 14, and an isolated expansion-chamber lo-
cated within said dome and concentric with
the said outlet-pipe.

Signed at Norwich, Connecticut, this 28th
day of May, 1900.

WILLIAM H. PAGE.
